US00D905041S

(12) **United States Design Patent** (10) **Patent No.:** **US D905,041 S**
Ahn (45) **Date of Patent:** **** Dec. 15, 2020**

- (54) **MOUNT ACCESSORY FOR ELECTRONIC DEVICE**
- (71) Applicant: **SPIGEN KOREA CO., LTD.**, Seoul (KR)
- (72) Inventor: **Deok Hyun Ahn**, Seoul (KR)
- (73) Assignee: **Spigen Korea CO., LTD.**, Seoul (KR)
- (**) Term: **15 Years**
- (21) Appl. No.: **29/685,532**
- (22) Filed: **Mar. 28, 2019**
- (51) **LOC (12) Cl.** **14-03**
- (52) **U.S. Cl.** **USPC** **D14/253**
- (58) **Field of Classification Search**
 USPC D14/251-253, 440, 447; D12/415; D8/354
 CPC F16M 13/00; F16M 2200/00
 See application file for complete search history.

(74) *Attorney, Agent, or Firm* — Heedong Chae; Lucem, PC

(57) **CLAIM**

The ornamental design for a mount accessory for electronic device, as shown and described.

DESCRIPTION

FIG. 1 is a front perspective view of a mount accessory for electronic device showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is another perspective view thereof shown in an environment of use; and,
 FIG. 9 is another perspective view thereof shown in an environment of use.
 The broken lines depict environmental subject matter only and form no part of the claimed design.

1 Claim, 9 Drawing Sheets
